UNITED STATES PATENT OFFICE.

JOSEPH N. WIGGIN, OF ORANGE, NEW JERSEY, AND JOHN E. RATHBUN, OF BROOKLYN, NEW YORK, ASSIGNORS TO SAID WIGGIN.

MACHINERY FOR HANDLING PRINTED SHADE FABRICS.

SPECIFICATION forming part of Letters Patent No. 449,305, dated March 31, 1891.

Application filed July 5, 1890. Serial No. 357,731. (No model.)

To all whom it may concern:

Be it known that we, JOSEPH N. WIGGIN, of Orange, in the county of Essex and State of New Jersey, and JOHN E. RATHBUN, of Brooklyn, in the county of Kings and State of New York, citizens of the United States, have invented a new and useful Improvement in Machinery for Handling Printed Shade Fabrics, and the following is declared

10 to be a description of the same.

Window-shade fabrics are prepared in large quantities for use by being cut into the lengths required, and part of the surface is printed upon and otherwise ornamented by 15 suitable designs and afterward dried. The shades are then secured to the rollers and sticks in the usual manner. A machine for printing upon such shade fabric and for delivering the same as printed is set forth in an 20 application for Letters Patent filed by J. N. Wiggin and Charles A. Collord, February 5, 1890, Serial No. 339,248, and duly allowed May 27, 1890, and in this machine slats or other sticks are employed to receive and convey 25 away the loop of shade fabric as delivered after printing.

The object of our present invention is to provide a mechanism for holding a quantity of sticks and for automatically delivering 30 such sticks to the shade-receiving mechanism of the machine described in the aforesaid application or to a shade-receiving mechanism for conveying the printed and ornamented shade from a bronzing or flocking machine.

35 We employ a receptacle or case for holding the rollers or sticks "en masse," in which there is a partition that allows a few sticks at a time to pass beneath it to an oscillating delivery-drum having a longitudinal groove 40 to receive a single stick. By the movement of this drum the sticks are delivered one at a time to two slideways, in which the ends of the stick rest. These slideways are inclined and are held up in place by springs against 45 stops, and each stick moves down these slideways to temporary stops that are withdrawn automatically, and the stick passes down to the lower end of the slides beneath spring-fingers. There are two swinging arms similar 50 to those in the aforesaid application. The upper ends of these arms are forked and

move adjacent to the inner edges of the slides, and fingers or projections above the forks press the stick or roller from beneath the spring-fingers and deliver it into the forked 55 ends of the arms, and such stick is carried to the place where the shade is delivered upon it, as in the aforesaid application. On the return movement the shade hangs upon the stick and between the arms, the stick being 60 longer than the width of the shade, and it is carried to a convenient place for the stick and shade to be removed from the arms by hand or automatically, and during this return movement another stick is delivered 65 from the hopper into the slideways ready to be taken by the forked ends of the arms.

In the drawings, Figure 1 is a longitudinal section of our improved machine. Fig. 2 is an elevation of one end of the stick-delivery 70 mechanism. Fig. 3 is a modification of the stick-receiving arm, and Fig. 4 is a modification of the stick-delivery mechanism, and Fig. 5 is a sectional plan of one end of the hopper and mechanism shown in Fig. 4. 75

The following parts are set forth in the aforesaid application, viz: the frames *o* to be connected to the floor or a standard, the swinging arms *r*, operating-arms *s*, shaft *9*, the bracket-hooks *r*² upon the ends of the arms *r*; 80 the adjustable rest-block *v*, the shaft *7*, sprocket-wheels *h*', and chain *i*. We have added the fingers *r*' and pins *r*³ at the ends of the swinging arms *r*.

a represents the case or hopper for holding 85 the sticks. This case or hopper is secured to the under side of the feed-table of the press for printing upon the shade fabric. This case is closed at the sides and open at the back end for the insertion of the sticks *a*'. Said case 90 or hopper is provided with a retaining-partition *b*, and *c* is an end board to said hopper *a*.

The drum or roller *d* is journaled in the side frames *a*² of the case or hopper or in a supplemental frame *a*³ and located partially within 95 said hopper, and said drum is provided with a single longitudinal groove at *d*', running from end to end, and upon the central shaft of the drum and at one end is a sprocket-wheel *e*. There is a sprocket-wheel *g* upon the shaft *9*, and a chain *f* passes around the sprocket-wheels *e* and *g* and is crossed, and 100

the backward and forward movement imparted to the arms r and shaft g , as described in the aforesaid application, imparts a similar motion to the sprocket-wheel g and chain f and a similar reciprocating motion in the opposite direction to the sprocket-wheel e and drum d .

k represents a roller-shaft located above and resting upon or adjacent to the surface of the drum d . This shaft k extends through slots in the respective sides a^2 of the hopper, and upon its ends are weight-wheels k' ; but these weight-wheels k' may be dispensed with.

The L-shaped slideways m are pivoted to hangers l , which are bolted to the faces of the end board c . These slideways m are located just beyond the ends of the drum, and are connected by a cross-strip m' . Helical springs n are connected at their ends to the end board c and slideways m and serve to hold up the slideways, and stops n' , in the form of bars depending from the under side of the feed-table B, limit the upward movement of the slideways.

25 The spring-fingers s' have angular ends by which they are connected to the sides of the slideways, and said fingers s' lie along parallel with said slideways, and their downwardly-bent ends serve to hold the descending sticks a' from passing out of the slideways m until pressed from beneath such springs, as hereinafter described.

t represents angular L-shaped spring-inclines, secured to the lower ends of the slideways and projecting backwardly.

30 Springs u are secured to the under side of the hopper a and extend forward past the respective ends of the drum d , and upon the ends of said springs u there are pins u' , standing up through openings in the lower members of the L-shaped slideways, and we provide studs upon the ends of the drum d to act upon said springs as the drum revolves to depress the springs u and pins u' .

45 The operation of the device, Figs. 1 and 2, is as follows: A stick a' being in the lower end of the slideways m and a piece of shade fabric s being delivered over the chains i and sprocket-wheels h' the arm r , sprocket-wheel g , and drum d are presumably being moved by the operating mechanism set forth in the aforesaid application in the direction of the arrows. As the arms r move forward, the pins r^3 move over the spring-inclines t and draw down the slideways m , bringing the stick a' into the path of the notched upper ends of the arms r . The fingers r' pass over the stick, and, forcing it from beneath the spring-fingers s' , deliver it into the notch of the hooks r^2 . The arms r now move forward, bringing the stick against the shade fabric and rest-block v , where the shade fabric is delivered upon the stick in the form of a loop. Simultaneously with this the sprocket-wheel g , chain f , and sprocket e have imparted a partial rotation to the drum d , which movement is slight, because of the relative

70 sizes of the said parts and the length of the arms r . The arms r , carrying the stick and loop of shade-fabric, now move backward to deliver the same to a conveyer or runway for drying. During the backward movement of the arms r the pins r^3 run under and raise the spring-inclines t , and the backward movement to the place where the stick and shade 75 are taken off is sufficient for turning the drum d in the opposite direction to the arrow and delivering another stick on the inclines m . This movement takes the studs 12 out of engagement with the springs u , so that said springs and the pins u' can return to their normal position, wherein the pins u' stand above the surface of the slideways m to arrest the stick as it runs down the inclines. Simultaneously with this movement of the 80 drum d the stick a' in the longitudinal groove d' is carried beneath the roller or shaft k , where, if the stick is bent, it will be forced into the groove and its delivery insured. With the further movement of the drum d , 85 the ends of the stick, which extend out beyond the ends of the drum, are brought against the slideways m and lifted out of the groove and delivered upon the slideways, when said stick slides down by gravity to the pins or 90 stops u' . The forward movement of the arms r operates the drum d again in the direction of the arrow, and the groove d' passes beneath the roller-shaft k within the hopper, where the first stick falls into the groove d' , to be 95 afterward delivered, as just described. Simultaneously with this movement the studs 12 depress the springs u and pins u' and free the stick on the slideway, which slides down to the ends beneath the fingers s' in 100 ample time for the forward movement of the arms r to take said stick, as heretofore described. These operations are continuously 105 repeated.

The device shown in Fig. 3 is a modification in the construction of the stick-receiving arms r , the object of which is to dispense with the fingers r' , as there is liability of said fingers being in the way when the stick and shade are delivered. In this device the frames o are extended to form bearings at 110, to which the arms r^5 are pivoted. The upper ends of the arms r^5 are curved and slotted, as shown, and one end of each pin r^3 passes through said slot. As the arms r move forward toward the press, the arms r^5 swing upwardly for their curved ends to engage the stick in the end of the slideways and remove the same into the notches of the hooks r^2 . With the backward movement of the arms r 115 the curved ends of the arms r^5 are drawn down out of the way below the extreme end of the arms r , so that the sticks and loops of shade fabric can be freely removed.

The modification shown in Fig. 4 relates to 120 the delivery of sticks from a hopper a^4 , having guiding-edges a^5 , by a grooved drum d to traveling belts or chains b^4 , upon which are fingers 20 at regular intervals. The sticks

pass out beneath the weighted roller-shaft *k*, and the movement of the parts are so timed that the fingers 20 engage the ends of each stick as delivered and carry the same upwardly over the pulleys 21 and along horizontally.

The shade fabrics as printed or ornamented are delivered from the machine in which such work is done to the inclined tapes 22 23, and by them are carried up and over the roller 24, the end falling over between the upper portion of the belts *b*⁴ and pulleys 21 and 25. The parts are timed so that a stick is presented by the fingers 20 to engage the central part of each shade. This figure shows the position of a stick and shade just before the end of the shade leaves the roller 24 and falls to form a loop upon the stick. The sticks and shades are delivered from the belts or chains *b*⁴ in any desired manner to devices for storing said loops of shade while drying. The pulleys 25 are notched for the fingers 20 to pass by on their return movement.

The tapes 22 23 are presumed to bring up three printed shades to one complete revolution of the belts *b*⁴, and it is to be understood that there are two belts *b*⁴, one for each end of the rollers, and that the pulleys 21, 25, and 28 are supported by gudgeons in suitable frames at opposite sides for the respective belts, so that there are not any crossing shafts to interfere with the shade fabric as it hangs between the belts *b*⁴.

We claim as our invention—

- 35 1. The combination, with a hopper for holding sticks, of a drum located partially within said hopper and grooved longitudinally, mechanism for imparting a partial rotary movement to said drum to engage and deliver one stick at a time, and with mechanism for engaging the respective ends of the sticks and presenting them for receiving in a loop the delivered shade fabric, substantially as set forth.
- 40 2. The combination, with a hopper for holding sticks, of a drum located partially within said hopper and having a single longitudinal groove to receive a single stick, an inclined retaining - partition *b*, the end board *c*, the weighted roller-shaft *k*, and mechanism, substantially as specified, for imparting a forward and backward movement to the drum, substantially as set forth.
- 45 3. The combination, with the hopper *a* for holding sticks, the drum *d*, and its operating sprocket-wheel and chain, of the slideways *m*, a spring *n*, and stop *n'* for holding up and limiting the movement of the slideways, pins for intercepting the descent of the sticks, and 50 spring-fingers for stopping and holding the

sticks at the lower end of the slideways, and mechanism, substantially as specified, for removing the sticks, substantially as set forth.

4. The combination, with the hopper *a* for sticks and the grooved drum *d*, of the sprocket-wheels *e* *g* and chain *f*, the arms *r*, having recessed upper ends, the sprocket-wheels and chains for delivering lengths of printed shade fabric, and a rest-block, and mechanism, substantially as specified, for delivering the shade-sticks one at a time from the grooved drum to the arms *r*, substantially as set forth.

5. The combination, with the hopper *a* for sticks and the inclined slideways *m*, of the drum *d*, located partially within the hopper and having a longitudinal groove, the springs *u*, the pins *u'*, working in openings in the slideways, and studs 12 on the respective ends of the drums for depressing the springs and pins, substantially as set forth.

6. The combination, with the hopper *a* for sticks, the grooved drum *d*, and movable arm *r*, and mechanism, substantially as set forth, for moving the parts in unison, of the hangers *l*, the slideways *m*, springs *n*, stops *n'*, the stick-retaining springs *s*, the inclined foot-plates *t*, and the finger or pin *r*³, substantially as set forth.

7. The combination, with the hopper *a* for sticks, of a drum located partially within said hopper and having a single longitudinal groove to receive a single stick at a time, the roller or shaft *k*, having slotted bearings and resting adjacent to the drum for insuring the delivery of every stick, and mechanism, substantially as specified, for imparting a rotary reciprocating movement to the drum, substantially as set forth.

8. The combination, with the pivoted slide-ways *m*, and springs *n* for holding up the same and springs *s* for holding the sticks, of the inclined foot-plates *t*, the arms *r*, the pins *r*³ for drawing down the slideways, and projecting fingers *r'* for removing the sticks, substantially as set forth.

9. The combination, with the hopper *a* for sticks and the drum *d*, of the slideways *m*, connected to the hopper, springs *s* at the lower end of the slideway for holding the sticks, the arms *r*, and projecting fingers connected to and operating with the movement of the arms *r* for engaging the sticks and depositing them in the ends of the arms *r*, substantially as specified.

Signed by us this 27th day of June, A. D. 1890.
